Henry V. Dorn, Brooklyn, N. Y., assignor to Western Electric Company, Incorporated, New York, N. Y., a corporation of New York

Application September 13, 1947, Serial No. 773,888

6 Claims. (Cl. 101—301)

1

This invention relates to a printing press, and more particularly to a press for printing indicia upon an unyieldingly hard surface with type of elastically yielding material without smudging or smearing.

In the art of manufacturing parts for and assembling complex electrical apparatus, e. g. for telephony, telegraphy, radio, radar, and the like, it is often the case that the principal supporting member or base for such an assembly is a plate or shallow tray of hard, rigid material, it may be of hard, rigid metal in some instances, or of hard, rigid, electrically insulating material in others, as, for example, hard fiber, hard rubber, or one of the polymeric resins, or other generally similar material. It is then often desirable to provide such laminar base members with visible indicia, it may be to identify the genus and class of the finished assembly, or to indicate what kind of unit is to be mounted where on the variously perforated plate, or for some other reason. It is further usually desirable, sometimes essentially necessary, that the indicia be not only clearly and cleanly placed, but also be accurately located thereon with respect to features thereof, within close tolerances.

An object of the present invention is to provide a simple, sturdy and reliable system of construction for a press to print indicia primarily on an unyieldingly hard surface with elastically yielding type clearly and cleanly, and to place the printed indicia in accurately predetermined position on the surface.

With the above and other objects in view the invention may be illustratively embodied in a printing press having a main frame, a printing bed unit supported on the frame to position an article to have indicia printed thereon, a printing plate unit having type thereon to print the indicia on the article, a linkage unit supported on the frame to support the plate unit and compel the same generally to approach to and recede from the article along an arcuate path, anti-friction members between one of said units and the immediate support therefor to enable the said one unit to float longitudinally of the main frame, a cam member rigidly mounted with respect to said printing bed unit, and a cam member to coact therewith and rigidly mounted with respect to said printing plate unit to compel such relative motion of these two units with respect to each other as will make the final approach of the printing plate to the printing bed and the initial recession of the printing plate from the printing bed to be along a direction perpendicular

2

to the plane of printing contact of type and article.

Other objects and features of the invention will appear from the following detailed description of embodiments thereof, taken in connection with the accompanying drawings, in which

Fig. 1 is a broken view in side elevation and partly in longitudinal vertical section of a hand operated printing press constructed in accordance with the invention;

Fig. 2 is a broken view thereof in horizontal section on the line 2—2 of Fig. 1;

Fig. 3 is an enlarged partial, broken, reverse plan view on the line 3—3 of Fig. 1;

Fig. 4 is a section on the line 4—4 of Fig. 3;

Fig. 5 is a plan view of a printed base plate;

Fig. 6 is a broken view in side elevation of a modified form;

Fig. 7 is an enlarged broken, partial reverse plan view on the line 7—7 of Fig. 6;

Fig. 8 is a broken, inside, side elevation on the line 8—8 of Fig. 7; and

Fig. 9 is a broken view in side elevation of another modified form.

25 The press disclosed herein to embody the invention is of a simple commercial form and apart from the features which embody the invention itself, is disclosed only in so far as is necessary for a complete description and understanding of the invention. The apparatus generally comprises a rigid framework mounted on casters 20

30 for convenience of removal from one job location to another, as desired in an extensive plant, and provided with levelling screws 21 to raise the casters out of operative position and to level and firmly position the apparatus for use.

35 Rollers 22 are journalled in the frame to lie transversely thereof and parallel to each other; and a printing bed, generally indicated at 23 rests 40 on these rollers near the front or right end of the frame and is freely movable thereon longitudinally of the frame. A spring 24 keeps the bed yieldingly a little leftward (Fig. 1) of its proper printing position when the bed is otherwise free. The bed may comprise, as shown, a rigid base plate 25 in which are formed guide

45 grooves 26 in which the rollers 22 run and prevent lateral or transverse motion of the bed. Transverse girders 27 are rigidly mounted on the base plate 25 and carry a rigid, metal top plate 28 on the upper surface of which is preferably mounted a moderately soft rubber surface plate 29. A longitudinal position member 30 and a transverse positioning member 31 are rigidly positioned on 50 the surface plate 29, so that an assembly base

plate 32 to receive printed indicia, when placed firmly against the two positioning members 30 and 31 will be in an accurately predetermined position on the bed 23.

An inking bed, generally indicated at 33, is generally similarly constructed and formed, and positioned on rollers 34 near the rear end of the frame (left in Fig. 1) to have longitudinal but not lateral freedom of motion relative to the frame. A spring 35 keeps the inking bed, when otherwise free, a little forward of its proper inking position. The inking bed comprises a base plate 36, transverse girders 37, a metal top plate 38, a layer of felt 39 cemented thereon, and a glass surface plate 40 cemented to the felt.

Four normally vertical links 41, 42, 43 and 44 are pivotally mounted in pairs on the opposite sides of the frame at 45 and 46; and a horizontal carrying frame 47 is pivotally attached at 48 and 49 to the upper ends of the links 41, 42, 43 and 44 so that while the carrying frame 47 is always parallel to the top surfaces of the printing bed and inking bed, it may be moved freely at will into either of the extreme positions indicated in Fig. 1 in broken lines at 51 and 52 in order to bring the printing plate generally indicated at 50 into contact with work on the printing bed 23 or into contact with ink on the top surface of the inking bed 33. The carrying frame 47 is yieldingly maintained in the inoperative middle position shown in full in Fig. 1 by means of a counterweighted lever 53 pivoted at 46 and rigid with the link 42. A transverse bar 54 is mounted in the frame 47 as a handle for manipulation of the frame.

The frame 47 is provided with rigidly attached horizontal flanges or lugs 55 and 56 having vertical cam apertures 57 and 58 formed therein. Vertical cam pins 59 and 60 are rigidly mounted on the bed 23; and identically similar vertical cam pins 61 and 62 are rigidly mounted on the bed 33.

The various parts thus far described are so arranged, connected, related and dimensioned that when an operator standing before the right (Fig. 1) end of the machine, pulls the handle 54 toward himself (forward) the frame 47 moves arcuately forward and down until the bevelled tops of the pins 59 and 60 enter the perforations 57 and 58 respectively. The pins are held a trifle back of their proper positions by the spring 24 at this moment; but the apertures 57 and 58 can register with the pins since the frame 47 has not yet reached the fully forward position of its arcuate path. As the frame 47 is forced on down, the rear faces of the pins 59 and 60 are held continuously engaged against the rear peripheries of the apertures 57 and 58 by the tension of the spring 24, as the lugs 55 and 56 continue to move slightly forward as well as down. Thus the lugs 55 and 56 compel the pins 59 and 60 and with them the bed 23 to move forward at exactly the same rate as the forward component of the motion of the printing plate 50. Thus while the pins 59 and 60 are engaged in the apertures 57 and 58 in the lugs 55 and 56 under the tension of the spring 24, there can be no relative horizontal displacement of the bed 23 and the printing plate 50. These approach to and recede from mutual contact in a direction perpendicular to both, guided by the rear faces of the pins 59 and 60. Especially during the actual contact of type members on the plate 50 with a base plate 32 to be printed and resting on the bed 23, there can be no slip of one on the other along the hori-

zontal plane of their contact, no smearing of the printed indicia.

In similar fashion, when the operator pushes the bar 54 away or backward, the frame 47 travels arcuately back and down; the lugs 55 and 56 engage the pins 61 and 62 in the apertures 57 and 58 and so force the inking bed 33 to accompany the backward horizontal component of motion of the printing plate 50 while the relative motion of the plate 50 and ink bearing glass 40 becomes one purely perpendicular to both. Thus the type approach to the ink surface, make contact thereon, and recede therefrom without any slip of one on the other along the contact plane. Hence no ink is scraped up upon the vertical sides of the type to smudge the next printing impression on a plate 32.

To round out the description, it may be noted that means such as the springs 63 may be provided to cushion too swift or forceful operation.

The particular apparatus disclosed is one designed and made to print indicia on metal base plates as illustrated in detail in Fig. 5. In such case a simple method of making the printing plate 50 as shown in detail in Fig. 3, is to take such a plate 32 and cement thereon in the desired predetermined locations, suitable, elastic type. Thus as shown in Fig. 4, the main member 25 of a plate 50 may be a plate 132 identically like the plate 32, having cemented thereon rubber type 64 having a type face 65 of solid soft rubber and an underbody 66 of sponge rubber.

In the modified form shown in Figs. 6 and 7, 35 the printing bed 123 and inking bed 133 are rigidly mounted on the machine frame while the printing plate 50 is directly mounted on an auxiliary frame 67 which is mounted in the frame 47 on rollers 68 to have longitudinal motion only 40 in the frame 47 under the influence of the two springs 69. The pins 59, 60, 61 and 62 are rigidly mounted as before in the beds 123 and 133. The cam apertures are formed in members of the frame 67 as indicated at cam aperture 157 in member 155 in Fig. 7. The manipulation in the case of this form of the machine is the same as before; but here the printing plate is floatingly movable and cammed into perpendicular approach to and recession from the beds 123 and 133, instead of vice versa.

In the third form, shown in Fig. 9, the beds 123 and 133 are rigid on the main frame; and the printing plate is rigid on the frame 47. But the links 41, 42, etc. which carry the frame 47 are pivoted on a carriage 70 which floats on the main frame on rollers 71 between opposed springs 169. Here the cam pin 159 is shown mounted on the frame 47 and the cam apertures 257 and 357 are shown in suitable members of the main frame. The precise form and nature of these coacting cam member pairs are not important to the invention so long as the desired cam effect is produced; nor is it in any way material to the invention whether the pin is below and the aperture above or vice versa. The essential feature of the invention is the provision of floating longitudinal freedom of motion against spring tension of the printing plate relative to the printing bed only if there is no inking bed, or to both beds if both are present, together with cam devices to compel the final approach to and first recession from each other of the printing plate and either bed to be along a mutually perpendicular direction regardless of what motions the 70 two may make together in other directions.

An inking roller 100 is located on a suitable inking arm 101 which is pivotally mounted at 49. When the printing plate 50 is moved to its printing position, the inking roller 100 moves over the right end of the inking bed 33, spreading and smoothing the ink at that end. As the printing plate 50 is moved to its inking position, shaft extensions 102 of the inking roller begin to ride on edges 103 of inclined runways 104. Since the shaft extensions 102 have a much smaller diameter than the inking roller, their movement on the inclined runways 104 have the effect of spinning the inking roller and causing a different part of its periphery to contact the inking bed each time the printing plate 50 is moved from the inking bed to its printing position. The use of these runways therefore overcomes the obviously bad situation of having a particular portion of the inking bed always contacted by the same part of the inking roller. A nut 105 and threaded extension 106 are used in conjunction with bracket 107 to increase or decrease the angle of the inclined runways 104.

What is claimed is:

1. In a printing press having a main frame, a printing bed unit supported on the frame to position an article to have indicia printed thereon, a printing plate unit having type thereon to print the indicia on the article, a linkage unit supported on the frame to support the plate unit and compel the same generally to approach to and recede from the article along an arcuate path, anti-friction members between one of said units and the immediate support therefor to enable the said one unit to float longitudinally of the main frame, a cam member rigidly mounted with respect to said printing bed unit and having its camming surface perpendicular to the printing bed, and a cam member to coact therewith and rigidly mounted with respect to said printing plate unit to compel such relative motion of these two units with respect to each other as will make the final approach of the printing plate to the printing bed and the initial recession of the printing plate from the printing bed to be along a direction perpendicular to the plane of printing contact of type and article.

2. In a printing press having a main frame, a printing bed unit supported on the frame to position an article to have indicia printed thereon, a printing plate unit having type thereon to print the indicia on the article, a linkage unit supported on the frame to support the plate unit and compel the same generally to approach to and recede from the article along an arcuate path, anti-friction members between one of said units and the immediate support therefor to enable the said one unit to float longitudinally of the main frame, a resilient member to maintain the floating unit yieldingly slightly out of operative position, a cam member rigidly mounted with respect to said printing bed unit and having its camming surface perpendicular to the printing bed, and a cam member to coact therewith and rigidly mounted with respect to said printing plate unit to compel such relative motion of these two units against the tension of the resilient member and with respect to each other as will make the final approach of the printing plate to the printing bed and the initial recession of the printing plate from the printing bed to be along a direction perpendicular to the plane of printing contact of type and article.

3. In a printing press having a main frame, a

printing bed unit supported on the frame to position an article to have indicia printed thereon, a printing plate unit having type thereon to print the indicia on the article, a linkage unit supported on the frame to support the plate unit and compel the same generally to approach to and recede from the article along an arcuate path, anti-friction members interposed between the printing bed unit and the main frame to enable the printing bed to float longitudinally of the frame, a cam member rigidly mounted with respect to said printing bed unit and having its camming surface perpendicular to the printing bed, and a cam member to coact therewith and rigidly mounted with respect to said printing plate unit to compel such relative motion of these two units with respect to each other as will make the final approach of the printing plate to the printing bed and the initial recession of the printing plate from the printing bed to be along a direction perpendicular to the plane of printing contact of type and article.

4. In a printing press having a main frame, a printing bed unit supported on the frame to position an article to have indicia printed thereon, a printing plate unit having type thereon to print the indicia on the article, a linkage unit supported on the frame to support the plate unit and compel the same generally to approach to and recede from the article along an arcuate path, anti-friction members interposed between the printing bed unit and the main frame to enable the printing bed to float longitudinally of the frame, a resilient member to maintain the floating unit yieldingly slightly out of operative position, a cam member rigidly mounted with respect to said printing bed unit and having its camming surface perpendicular to the printing bed, and a cam member to coact therewith and rigidly mounted with respect to said printing plate unit to compel such relative motion of these two units against the tension of the resilient member and with respect to each other as will make the final approach of the printing plate to the printing bed and the initial recession of the printing plate from the printing bed to be along a direction perpendicular to the plane of printing contact of type and article.

5. In a printing press having a main frame, a printing bed unit supported on the frame to position an article to have indicia printed thereon, an inking bed unit supported on the main frame, a printing plate unit having type thereon to print the indicia on the article, a linkage unit supported on the frame to support the plate unit and compel the same generally to approach to and recede from the article and the inking bed alternatively along an arcuate path, anti-friction members interposed between the printing bed unit and the main frame to enable the printing bed to float longitudinally of the frame, anti-friction members interposed between the inking bed unit and the main frame to enable the inking bed to float longitudinally of the main frame, a cam member rigidly mounted with respect to said printing bed unit and having its camming surface perpendicular to the printing bed, a cam member rigidly mounted with respect to said inking bed unit and having its camming surface perpendicular to the inking bed, and a cam member to coact alternatively with said first and second mentioned cam surfaces and rigidly mounted with respect to said printing plate unit to compel such motion of the printing plate unit with respect alternatively to the printing bed

75

unit and to the inking bed unit that the final approach of the printing plate to and its initial recession from either bed will be along a direction perpendicular to the plane of contact therewith.

6. In a printing press having a main frame, a printing bed unit supported on the frame to position an article to have indicia printed thereon, an inking bed unit supported on the main frame, a printing plate unit having type thereon to print the indicia on the article, a linkage unit supported on the frame to support the plate unit and compel the same generally to approach to and recede from the article and the inking bed alternatively along an arcuate path, anti-friction members interposed between the printing bed unit and the main frame to enable the printing bed to float longitudinally of the frame, anti-friction members interposed between the inking bed unit and the main frame to enable the inking bed to float longitudinally of the main frame, resilient members to maintain the floating units yieldingly slightly out of operative position, a cam member rigidly mounted with respect to said printing bed unit and having its camming surface perpendicular to the printing bed, a cam member rigidly mounted with respect to said inking bed unit and having its camming surface perpendicular to the inking bed, and a cam member to coact alternatively with said first and second mentioned cam surfaces and rigidly mounted with respect to said printing plate unit to compel

such motion against the tension of the resilient members and of the printing plate unit with respect alternatively to the printing bed unit and to the inking bed unit that the final approach of the printing plate to and its initial recession from either bed will be along a direction perpendicular to the plane of contact therewith.
